UNITED STATES PATENT OFFICE.

ELLIS J. HANNUM, OF PHILADELPHIA, PENNSYLVANIA, ASSIGNOR TO
NEWTON MACHINE TOOL WORKS, INCORPORATED, OF PHILADEL-
PHIA, PENNSYLVANIA, A CORPORATION OF PENNSYLVANIA.

SPEED-BOX FOR METAL-WORKING MACHINES.

No. 857,899.

Specification of Letters Patent.

Patented June 18, 1907.

Application filed November 8, 1906. Serial No. 342,469.

To all whom it may concern:

Be it known that I, ELLIS J. HANNUM, a citizen of the United States, residing in Philadelphia, Pennsylvania, have invented certain Improvements in Speed-Boxes for Metal-Working Machines, of which the following is a specification.

My invention relates to certain improvements in speed boxes for metal working machines containing speed change gears and situated between the driving shaft and the power shaft so as to regulate the speed of the machine.

The object of my invention is to improve the construction of speed change gears of the above type so that they can be readily operated to vary the speed of the machine and will be compact taking up very little space on the machine.

In the accompanying drawing:—Figure 1, is a sectional plan view of my improved speed change gear; Fig. 2, is a section on the line 2—2, Fig. 1; Fig. 3, is a plan view showing the operating levers; Fig. 4, is a sectional view on the line 4—4, Fig. 3; and Fig. 5, is a sectional view on the line 5—5, Fig. 3.

A is the casing of the speed box, B is the power shaft, C is the driving shaft and D is the driven shaft.

The power shaft B is mounted in bearings a, a on the casing A and on this shaft is a worm b, which meshes with a worm wheel c on the driving shaft C which is adapted to bearings a' in the casing A.

The driven shaft D is mounted in bearings a² in the casing A and projects through the casing at one end. On this end of the shaft in the present instance is a gear wheel d which meshes with the driving mechanism of the machine to which the speed box is applied.

The driving shaft C is splined as illustrated, and on the shaft is a sleeve E having a small pinion e and a pinion e' a trifle larger than the pinion e, and secured to an extended hub of the sleeve E is a gear wheel e² having a groove e³ in its hub to which is applied the shifting block f of the lever F. The lever F is pivoted at f² to the plate A' and the block f in this instance is swiveled in an arm f' of the lever which passes through a slot a³ in the top plate A', as clearly illustrated in Fig. 3, and can be locked in its adjusted position by

the bolt f³ which may enter any one of the holes in the segment g on the plate A'. This bolt is moved by means of a spring latch f⁴ pivoted to the handle of the lever F, as illustrated in Fig. 5.

The driven shaft D is splined throughout its length and on this shaft is a sleeve H having a pinion h at one end and a pinion h' at the opposite end larger than the pinion h and secured to the hub of this sleeve is a gear wheel h². The sleeve is grooved at h³ and adapted to this groove is a block i swiveled in the arm i' of a shifting lever I pivoted at i² to the plate A'. This lever carries a bolt i³ which enters openings in the segment g' on the plate A' and is operated by a spring latch i⁴ carried by the handle portion of the lever I. So that the lever can be locked in either of its three positions.

G is an intermediate shaft preferably fixed in bearings a⁵ in the casing of the speed box. On this shaft is a hub K having a small pinion k and intermediate pinion k' and a gear wheel k², the gear wheel being secured to the extended portion of the hub K as illustrated.

K³ is a bushing forced into the hub and of a different metal from the shaft G so that it will turn freely on said shaft.

The wheels e², h² and k² in the present instance are secured to the hubs by screws tapped partly in the ends of the wheels, and partly in the hubs, as indicated in Fig. 1, but other means for fastening these wheels may be resorted to without departing from my invention. In fact in some instances the three wheels or pinions may be cast in one piece.

It will be noticed that the sleeves E and H are longitudinally adjustable on their respective shafts, while the hub K is held from longitudinal movement by means of the bearings a⁵, although it is free to turn on its shaft G.

Thus it will be seen that by shifting the levers F and I the speed can be changed by throwing certain gears into action, for instance, as illustrated in Fig. 1, the pinion e' is in mesh with the pinion k' and the pinion k is in turn in mesh with the wheel h² on the sleeve D, so that the drive is through these respective gears.

If it is desired to increase the speed the

sleeve E can be shifted so that the pinion e^2 will mesh with the pinion k and if it is wished to still further increase the speed the sleeve H can be shifted so that the pinion k' will mesh with the pinion k' , or the pinion h will mesh with the pinion k^2 , and if it is wished to reduce the speed then the sleeve E can be shifted so as to throw the pinion e in mesh with the wheel k^2 .

10. Thus it will be seen that many changes can be made in the speed by simply shifting either of the levers F and I, or both of them.

I claim:—

1. The combination in a speed box, of a casing, a driven shaft mounted in the casing, a power shaft, a driving shaft arranged at right angles to the power shaft, a worm on the power shaft, a worm wheel on the driving shaft meshing with the said worm, an intermediate shaft between the driving shaft and the driven shaft, a hub on said intermediate shaft, a sleeve arranged to slide longitudinally on the driving shaft, a series of gears thereon, a series of gears on the intermediate hub and arranged to mesh with the gears on the sleeve of the driving shaft when the said sleeve is shifted to certain positions, a sleeve on the driven shaft having a series of gears also arranged to mesh with the gears

on the hub when shifted in certain positions, and means for shifting the two sleeves, substantially as described.

2. The combination in a speed box, of a casing, a driving and a driven shaft mounted in bearings in the casing, an intermediate shaft also mounted in bearings in the casing and situated between the driving and driven shafts, a hub on the intermediate shaft, a sleeve on the driving shaft and a sleeve on the driven shaft, a series of gears on the hub and a series of gears on each sleeve, said gears differing in diameter, and two levers pivoted to the casing, each lever having an arm projecting through a slot in the casing and having blocks, the block of one lever engaging the sleeve on the driving shaft and the block of the other lever engaging the sleeve on the driven shaft, and means for locking the levers in their adjusted positions, substantially as described.

In testimony whereof, I have signed my name to this specification, in the presence of two subscribing witnesses.

ELLIS J. HANNUM.
